UNITED STATES PATENT OFFICE.

WINTON A. DEAN AND ARTHUR L. DEAN, OF LONG BEACH, CALIFORNIA.

MILK AND CREAM SEPARATOR.

Application filed October 29, 1927. Serial No. 229,642.

This invention aims to provide a novel device adapted to be placed in a milk bottle or like container, to separate the milk from the cream, so that the cream may be poured off. The invention aims to improve the construction of the separator, and to provide novel means for operating the separator so that it can be turned into a position in which it can be inserted readily into the restricted 10 neck of a milk bottle.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described 20 and claimed, it being understood that changes in the precise embodiment of the invention herein disclosed may be made within the scope of what is claimed, without departing from the spirit of the invention.

In the drawings:—

Figure 1 shows in side elevation, a device constructed in accordance with the invention;

Figure 2 is an elevation wherein the structure is viewed at right angles to the showing of Figure 1;

Figure 3 is a transverse section wherein the separator appears in top plan;

Figure 4 is a bottom plan of the separator;

Figure 5 is a sectional view showing the parts as they will appear whilst the separator is being inserted into the neck of the bottle;

Figure 6 is a top plan of the structure arranged as shown in Figure 5, parts being in section.

The device forming the subject matter of this application includes a support or standard 4, in the form of a rod, the lower end of 45 the support 4 being flattened as shown at 11, and being twisted as indicated at 27, to form an anchor and stop 28. At its upper end, the support 4 has a handle in the form of a finger loop 5. The numeral 1 marks an 50 operating member, which may be a rod, provided at its upper end with a finger loop or handle 2. The operating member 1 is supplied at a point near its upper end with a transverse guide 3 mounted on the support 55 4. The construction is such that the operating member 1 can slide longitudinally on the

support 4 and also swing a little, to an acute angle with respect to the support 4, as shown in Figure 5 of the drawing. There is a washer 6 on the support 4. A compression 60 spring 7 surrounds a portion of the standard 4, one end of the compression spring 7 abutting against the washer 6, and the opposite end of the spring abutting against the guide 3 on the operating member 1 65

The numeral 12 marks a disk like separator 12, including a flexible body 14, made of rubber or similar material. An intermediate reinforcing plate 15, preferably made of metal, is mounted on the upper surface of the body 14. A corresponding intermediate lower reinforcing plate 16 cooperates with the lower surface of the body 14, and the intermediate plates 15 and 16 are connected, through the body 14, by securing 70 elements 17. Upper lateral reinforcing plates 18 are mounted on the upper surface of the flexible body 14, and on the lower surface of the body 14 are mounted lower lateral reinforcing plates 19, the plates 18 75 and 19 preferably being made of metal, and being connected, through the body 14, by securing elements 20. The longitudinal edges of the plate 16 (Figure 4) are spaced, as at 21, from the longitudinal edges of the 80 plates 19. In a similar way, as shown in Figure 3, the longitudinal edges of the plate 15 are spaced from the longitudinal edges of the plates 18. The construction is such that although the separator 12 may be folded along two lines parallel to the line A—B in Figure 4, the separator is rigid in a direction at right angles to the line A—B. The plates 16—19—15—18 form metal reinforcements of less area than the flexible body 14, 90 so that there is left a flexible margin 22 in the body 14, this margin being adapted to make a tight fit when the article is introduced into a milk can.

The reinforcing plate 16 has a hole 23 that 100 registers with a hole 24 in the flexible body 14 of the separator 12. The plate 15 of the separator has a notch 25 that exposes the hole 24 in the body 14. A rectangular lip 26 is formed on the plate 15 at the base of the notch 25 and overhangs the hole 24. An arm 8 is formed on the plate 15 at the base of the notch 25 and extends away from the plate 16, in a direction at right angles thereto. The arm 8 is pivoted at 10 to the 110 part 11 of the support 4. The lower end of the operating member 1 is pivotally connect-

ed at 9 with the arm 8 at a point intermediate the ends of the arm. The arm 8 and the pivot elements 9 and 10 constitute means whereby the operating member 1 and the standard 4 are pivotally connected with the separator 12 in off-set relation to the separator. The links 29 are pivotally connected with the part 28 of the support 4, and it is on this account that the part 28 is alluded to as an anchor. The links 29 diverge from the part 28 and are pivotally connected with ears 30 on the plates 18 of the separator 12.

The spring 7 expands and produces relative longitudinal movement between the operating member 1 and the standard 4, until the arm 8 of the separator 12 abuts against the top 28 on the lower end of the support 4. Under such circumstances, the separator 12 stands at right angles to the parts 1 and 4, as indicated in Figure 2.

In using the device, the thumb and one of the fingers of an operator are placed in the loops 5 and 2, and relative longitudinal movement between the standard 4 and the operating member 1 is brought about. This operation tilts the separator 12 until it stands about parallel with the operating member 1 and the support 4, and, at the same time, the links 29 cause the separator to fold into trough-shape, as shown in Figure 6. The separator, then, may be slid downwardly into a bottle of milk, and when one of the loops 5—2 is released, the spring 7 will expand, producing relative longitudinal movement between the parts 1 and 4 and opening out the separator 12 flat, as shown in Figure 1, between the milk and the cream in the bottle. Thereupon, the cream, which is above the separator 12 may be poured off.

Whilst the cream is being poured out of the bottle, no appreciable amount of milk will flow through the registering holes 23 and 24 of the separator 12, because no air

can get in through the holes 23—24. When, however, the cream has been poured off, and when it is desired to remove the separator 12 from the milk bottle, the holes 23—24 permit the milk to get through the separator 12, and the folding of the separator into the position shown in Figure 5, for removal, will be facilitated accordingly.

What is claimed is:—

1. In a device of the class described, a support, an operating member, means for connecting the support and the operating member for relative longitudinal movement, a foldable separator, means for connecting the support and the operating member pivotally to the intermediate portion of the separator in off-set relation to the separator, links forming a pivotal connection between the support and the side portions of the separator, and spring means for imparting relative longitudinal movement to the support and to the operating member to dispose the separator flat and in a position approximately at right angles to the support, and to the operating member.

2. In a device of the class described, a foldable separator, the intermediate portion of which is provided with a projecting arm, a support pivoted to the outer end of the arm at a point intermediate the ends of the support, links forming a pivotal connection between one end of the support and the side portions of the separator, an operating member, means for mounting the operating member on the support for movement longitudinally of the support, and means for pivotally connecting the operating member with the arm at a point intermediate the ends of the arm.

In testimony that we claim the foregoing as our own, we have hereto affixed our signatures.

WINTON A. DEAN.
ARTHUR L. DEAN.
